UNITED STATES PATENT OFFICE.

DAVID D. BUICK, OF DETROIT, MICHIGAN.

DESIGN FOR A BATH-TUB.

SPECIFICATION forming part of Design No. 26,084, dated September 22, 1896.

Application filed August 5, 1896. Serial No. 601,820. Term of patent 14 years.

To all whom it may concern:

Be it known that I, DAVID D. BUICK, a citizen of the United States, residing at Detroit, in the county of Wayne and State of Michigan, have invented and produced a new and original Design for a Bath-Tub, of which the following is a specification, reference being had thereto to the accompanying drawings, in which—

10 Figure 1 is an end elevation, and Fig. 2 is a side elevation.

The leading feature of my bath-tub is the configuration.

15 A is the tub, having the flat top B, the inclined front end C, the bottom D, and the substantially vertical end wall E.

Near the top is the end extension F, having a horizontal top and the curved bottom G, which is substantially the section of a sphere, as shown in Fig. 1.

20

What I claim as my invention is—

The design for a bath-tub substantially as herein described and shown.

In testimony whereof I affix my signature in presence of two witnesses.

DAVID D. BUICK.
